DESCRIPTION

FIG. 1 is a right side elevational view of a pencil sharpener accessory for a tape measure showing my new design, the tape measure depicted by means of broken lines being for illustrative purposes only and forming no part of the claimed design;

FIG. 2 is a left side elevational view;

FIG. 3 is a top plan view;

FIG. 4 is a rear elevational view;

FIG. 5 is a front elevational view; and,

FIG. 6 is a bottom plan view thereof.
